DESIGN FOR A PENCIL

Frank C. Deli, Chicago, Ill.

Application July 15, 1935, Serial No. 57,643

Term of patent 14 years

To all whom it may concern:

Be it known that I, Frank C. Deli, a citizen of the United States, residing at Chicago, in the county of Cook and State of Illinois, have invented a new, original, and ornamental Design for a Pencil, of which the following is a specification, reference being had to the accompanying drawing, forming part thereof.

Fig. 1 is a front elevation of a pencil showing my new design; and

Fig. 2 is a side elevation of the same.

The dominating features of my design reside in providing the round barrel of a pencil with three angularly arranged juxtaposed plane surfaces near its upper end, and a clip and attaching means arranged to harmoniously cooperate with the said plane surfaces.

I claim:

The ornamental design for a pencil, as shown and described.

FRANK C. DELI.
